UNITED STATES PATENT OFFICE.

ERNEST F. LLOYD, OF DETROIT, MICHIGAN.

MERCURY-LOADER.

1,132,593.

Specification of Letters Patent. Patented Mar. 23, 1915.

Application filed February 14, 1911. Serial No. 608,487.

To all whom it may concern:

Be it known that I, ERNEST F. LLOYD, a citizen of the United States of America, residing at Detroit, in the county of Wayne 5 and State of Michigan, have invented certain new and useful Improvements in Mercury-Loaders, of which the following is a specification, reference being had therein to the accompanying drawings.

10 This invention relates to a loader for a valve governing the flow through a main or through any form of apparatus whereby the valve is made to operate through the medium of or in accordance with variations in 15 the drop in pressure in a moving column of fluid.

The invention consists in the matters hereinafter set forth and more particularly pointed out in the appended claims.

20 In the drawings, Figure 1 is a view partially in elevation and partially in section of one form of apparatus embodying features of the invention, showing the parts in the positions assumed when the valve to be controlled is fully loaded; Fig. 2 is a corresponding view showing the parts in the positions assumed when the control valve is not loaded; Fig. 3 is a view partly in section and partly in elevation of a modification 30 of the device; and Fig. 4 is a plan view of the apparatus shown in Fig. 3.

As herein indicated a valve 1 of any preferred type is operated by a diaphragm 2 to close under certain conditions of pressure, 35 the diaphragm being secured in the usual manner in a drum or shell 3. The diaphragm has a cup 4 which is shielded by an upper casing 5 and may, if desired, be provided with removable weights 6 that constitute 40 a constant load on the diaphragm whereby it operates when under a predetermined pressure. A governor drum 7 is divided into two closed compartments by a flexible diaphragm 8. The upper compartment 45 is in communication through a pressure pipe 9 with a high pressure or inlet arm of a conduit 10, the fluid passing through the latter being the medium whose variations in pressure are to control the valve 1. The other compartment below the diaphragm 8 is in communication with the circuit through a low pressure pipe 11 which opens into the conduit at a point beyond 50 the entrance of the pressure pipe 9.

thereto. If there is no obstruction, elbow, 55 valve or other means which occasions a difference in pressure between the points at which the pipes 9 and 11 are in communication with the conduit, the exhaust pipe 11 may conveniently be connected to the throat 60 of the Venturi pipe indicated at 12 forming a by-pass around a restriction or valve 13 placed in the main on the outlet side of the pressure pipe 9. The downward movement of the diaphragm 8 may be limited by 65 an adjustable stop 14 which as herein disclosed may conveniently be in the form of a rod screwthreaded through the base of the drum 7, with a check nut 15 to secure it in adjusted position. 70

A float chamber 16 is secured on the cover 17 of the drum 7 and is provided with an open tube 18 in which a stem 19 secured to the diaphragm 8 is freely reciprocable. A float 20 is secured on the stem 19 and is provided with a central aperture to clear the tube 18 and with a sealing tube 21 closed at its upper end and adapted at its lower end to project below the float into liquid contained in the float chamber to form with 80 the tube 18 a liquid seal that prevents the escape of gas from the upper compartment of the drum 7. Preferably the float 20 is annular or at least is of such dimensions as to leave a narrow interval only between the 85 wall of the float chamber and the outer face of the float. The upper end of the stem extends through an opening in the cover 22 on the float chamber and is attached by a flexible connecting member 23 to the end of a walking beam or balance lever 24. The ends of the latter are preferably segmental to avoid change in the length of the balance arm when the latter is in oblique position. 95

A counterbalance tank 25 is hung by a flexible member 26 to the other end of the balance arm 24 and is provided with a discharge nozzle 27 at its lower end. The latter is connected by a flexible pipe or hose 100 28 to a nipple passing through the wall of the shield 5 on the valve 1. A flexible hose 30 couples the inner end of the said nipple with an inlet pipe 31 extending into an annular channel indicated at 32 in the base of 105 the valve cup 4. Preferably the inlet 31 is disposed at some distance from the said nipple so that there is a sufficient length of

flexible connection 30 to permit free movement of the diaphragm and cup. The flow through the nipple 27 is controlled by an adjustable valve 34 of any preferred type. 5 The parts are so disposed that when the difference in pressure between the pressure pipe 9 and the exhaust pipe 11 due to the flow in the conduit is at a predetermined or desired point, the controlling valve 1 is open or at least is subject only to the effect of its diaphragm 2 and the superposed weights 6. If however, this difference in pressure increases the master diaphragm 8 draws the float 20 into the liquid contained in the 10 chamber 16 against the buoyant effect of that liquid and thereby raises the counterbalance tank 25. This causes liquid therein, which is preferably mercury, to flow into the cup of the controlling valve and thereby increase the load on the latter and depress it against the pressure that supports the valve diaphragm 2. Decrease in difference in pressure between the pressure pipe 9 and the exhaust pipe 11 reverses the operation, depresses the tank 25 and allows the 15 mercury or other liquid to flow out of the valve cup. The velocity of flow may be regulated by the valve 34 to prevent sudden oscillation of the apparatus and the downward range of movement of the master diaphragm 8 is also determined by the stop 14.

In Fig. 3 a modification is shown wherein the movement of the main diaphragm displaces liquid in the float chamber and causes it to flow on to the controlling valve. In preferred form such an arrangement of the apparatus includes a main drum 35 divided by a flexible main diaphragm 36 into an upper and lower compartment respectively 20 in communication with the high and low pressure points of a conduit through the pressure pipe 37 and exhaust pipe 38. A stem 39 from the diaphragm extends upwardly and loosely through the tube 40 into a float tank 41 mounted on a cover 42 of the drum 35. A float 43 that nearly fills the chamber 41 is secured to the upper end of the stem 39 by a pipe 44 that loosely encircles the tube 40 and forms therewith a liquid seal when its lower end is immersed in liquid in the chamber. A pipe 45 connects the float chamber with the upper portion of a diaphragm drum 46 mounted on the casing of a controlling valve 47 similar to the valve 1. The valve itself is operated by a diaphragm 48 on which there is a cup 49 in communication through an inlet nipple 50, flexible hose 51 and fitting 52 with the pipe 45. A shield 53 protects the drum and movable weights 54 may be placed on the cup if desired. A valve 55 controls the flow through the pipe 45. By the latter method of construction movement of the diaphragm 36, which may be limited by an adjustable stop 56 causes the displacement of a greater

or less volume of fluid in the chamber 41. When the liquid rises above a predetermined level it flows into the cup 49 of the valve 47 and thereby tends to overcome the lifting effect of the diaphragm 48.

Obviously, changes in the details of construction may be made without departing from the spirit of the invention and I do not care to limit myself to any particular form or arrangement of parts.

I claim as my invention:

1. In gas apparatus, a fluid pressure actuated controlling valve, a liquid holder weighting the valve, a conduit, an adjutage in the conduit, a reciprocable member moving in response to variations in the drop in pressure past the adjutage, a loading liquid container, a displacement member operated by the reciprocating member to vary the level of the liquid in the container and a conduit 85 between the container and the holder whereby the levels of liquid in the two vary correspondingly.

2. In gas apparatus, a fluid pressure actuated controlling valve, a liquid holder weighting the valve, a loading liquid container in communication with the liquid holder, a displacement member movable in the liquid container, and means adapted to be operated by variations in the drop in pressure in a moving column of fluid and adapted to move the displacement member.

3. In gas apparatus, loading means comprising a drum, a movable diaphragm dividing the drum into two compartments, a float chamber on the drum, a stem on the diaphragm passing through the float chamber, a float on the stem in the chamber, pipes each leading from a compartment of the drum, a liquid holder adapted to form a weight for a valve, and means arranged to vary the level of a loading liquid in the holder in response to movements of the float.

4. In gas apparatus, loading means comprising a drum, a movable diaphragm dividing the drum into two compartments, a float chamber on the drum, a stem on the diaphragm passing through the float chamber, a float on the stem in the chamber adapted to form a liquid seal for the stem, pipes each leading from a compartment of the drum, a liquid holder adapted to form a weight for the valve, and means arranged to vary the level of a loading liquid in the holder in response to movements of the float.

5. In gas apparatus, loading means comprising a drum, a movable diaphragm dividing the drum into two compartments, a float chamber on the drum, a stem on the diaphragm passing through the float chamber, a float on the stem in the chamber, pipes each leading from a compartment of the drum, a liquid holder adapted to form a weight for a valve, means arranged to vary the level of a loading liquid in the holder in response to

movements of the float, and an adjustable stop in the drum adapted to limit the movement of the diaphragm in one direction.

6. In gas apparatus, a governing drum, a movable diaphragm dividing the drum into two compartments, a float chamber on the drum, an open tube extending from the upper compartment of the drum into the float chamber, a stem on the diaphragm extending through the tube, an apertured float secured on the stem over and around the tube, a liquid holder adapted to form a valve weight, and means between the holder and float chamber adapted to change the level of a loading liquid in the holder in accordance with the movements of the float.

7. In gas apparatus, a governing drum, a movable diaphragm dividing the drum into two compartments, a float chamber on the drum, a stem on the diaphragm extending into the float chamber, a float on the stem in the chamber, a diaphragm for operating the valve, a liquid holder on the diaphragm, a shield for the holder, a pipe connecting a nipple on the shield with the float chamber, and a flexible pipe connecting the nipple on the shield with a liquid holder.

8. In gas apparatus, a governing drum, a diaphragm dividing the drum into two compartments, a float chamber on the drum, a stem extending from the diaphragm into the float chamber, a float on the stem forming with the drum a liquid seal for the stem, a valve, a movable diaphragm for operating the valve, a liquid holder weighting the valve diaphragm and operative connections between the float chamber and the liquid holder adapted to vary the level of a loading liquid in the holder in accordance with the movements of the float.

9. In gas apparatus, a governing drum, a diaphragm dividing the drum into two compartments, a float chamber on the drum, a stem extending from the diaphragm into the float chamber, a float on the stem forming with the drum a liquid seal for the stem, a valve, a movable diaphragm for operating the valve, a liquid holder weighting the valve diaphragm, operative connections between the float chamber and the liquid holder adapted to vary the level of a loading liquid in the holder in accordance with the movements of the float, a conduit, a pipe connecting the upper compartment with a point

in the conduit and a pipe connecting the lower compartment with a point of lower pressure in the conduit.

10. In gas apparatus, a governing drum, a diaphragm dividing the drum into two compartments, a float chamber on the drum, a stem extending from the diaphragm into the float chamber, a float on the stem forming with the drum a liquid seal for the stem, a valve, a movable diaphragm for operating the valve, a liquid holder weighting the valve diaphragm, operative connections between the float chamber and the liquid holder adapted to vary the level of a loading liquid in the holder in accordance with the movements of the float, a conduit, a pipe connecting the upper chamber of the drum with a point of the conduit, an adjutage in the conduit on the low pressure side of the point of connection with said pipe, a Venturi pipe forming a by-pass around the adjutage, and a pipe connecting the throat of the Venturi with the lower compartment of the drum.

11. In gas apparatus, a governing drum, a movable diaphragm dividing the drum into two compartments, a float chamber on the drum, a stem extending from the diaphragm into the float chamber, a float on the stem in the chamber, a controlling valve, a diaphragm for operating the controlling valve, a liquid holder weighting the diaphragm, means controlled by the float and adapted to change the level of a weighting liquid in the holder in accordance with the movement of the float, and means for regulating the rate of change of the liquid level independently of the movements of the float.

12. In gas apparatus, a governing drum, a movable diaphragm dividing the drum into two compartments, a float chamber on the drum, a stem extending from the diaphragm into the float chamber, a float on the stem within the chamber, a valve, a diaphragm controlling the valve, a liquid holder weighting the diaphragm, and flexible connections maintaining communication between the holder and the float chamber.

In testimony whereof I affix my signature in presence of two witnesses.

ERNEST F. LLOYD.
